UNITED STATES PATENT OFFICE.

ARO M. HARVEY, OF KANSAS CITY, MISSOURI.

AUTOMATIC CROSSING GATE.

Application filed January 27, 1922, Serial No. 532,169. Renewed September 5, 1925.

To all whom it may concern:

Be it known that I, ARO M. HARVEY, a citizen of the United States, residing at Kansas City, in the county of Jackson and State of Missouri, have invented certain new and useful Improvements in Automatic Crossing Gates; and I do hereby declare the following to be a full, clear, and exact description of the invention, such as will enable others skilled in the art to which it appertains to make and use the same.

The present invention relates to railway crossing gates, such as are used for closing a highway or road where it crosses a railway track, and the invention aims to provide a novel and improved apparatus for automatically operating the gates when the trains approach and pass the crossing.

Another object of the invention is the provision of a novel electrical apparatus for controlling the opening and closing movements of the gates, with electrical circuits controlled by trains approaching and passing the crossing, in order that the gates are operated entirely automatically, without the necessity for a crossing attendant or watchman.

A further object is to provide such an apparatus which will cause the gates to be closed by the approach of a train toward the crossing in either direction on the same track, which will permit the gates to open when the train reaches or passes the crossing and which will control the gates independently from a plurality of tracks, in order that when a train on one track is broken at the crossing to permit traffic across the tracks, the approach of a train on the other track will result in the gates being closed, and also, causing the closing of the gates by the approach of another train on the second track when a train is passing the crossing with the gates opened.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Fig. 1 is a diagrammatic view of the apparatus.

Fig. 2 is a plan view of one of the crossing gates, showing the stand and other parts in section.

Fig. 3 is an enlarged vertical section of the gate and stand, portions being broken away and portions shown in elevation.

Fig. 4 is a plan view of one of the electromagnetic switches.

Fig. 5 is a side elevation of such switch. The gates for the highway or road crossing the railroad may be of any suitable kind, and, as shown, the gates 10 are mounted on rock shafts 11 journaled in the gate stands 12, for the upward and downward swinging movement of the gates to open and closed positions at the opposite sides of the tracks.

In order to actuate the gates, a gear wheel 13 is secured on each shaft 11 within the corresponding stand 12, and opposite racks 14 and 15 mesh with said gear wheel and are slideable vertically in the stand. The gate 10 is weighted so as to swing open upwardly of itself, and the gate is swung downwardly to closed position by an electric motor, which, as shown, includes a core 16 secured to the lower end of the rack 14 and movable within a solenoid 17, whereby when said solenoid is energized electrically, the core is drawn down to turn the gear wheel 13 and swing the gate down, as seen in Fig. 3. When the solenoid is deenergized, the gate will return to open position.

The movement of the gate is retarded, to prevent the excessive movement of the gate and the sudden stopping thereof when opened and closed. For this purpose, a piston or plunger 18 is secured to the lower end of the rack 15 and works within a dash pot 19 mounted in the lower portion of the stand 12 beside the solenoid 17. The movement of the gate is thus slowed down, and the gate cushioned at the limits of opening and closing movements.

An electric lamp 20 is preferably mounted on each gate, and is disposed in a circuit 21 with a battery 22 or other source of electrical energy, and such lamp is lighted when the gate is swung downwardly to closed position. Thus, one terminal of the circuit 21 is connected to a contact 23 and the other terminal is connected to an arcuate contact strip 24 secured on a wheel or drum 25 secured to the corresponding shaft 11, in order that when the gate is swung

downwardly the contact strip 24 is moved into engagement with the contact 23, to close the circuit of the lamp. When the gate is swung upwardly to open position, the contact strip 24 is removed from the contact 23, thereby opening the circuit of the lamp and extinguishing the light. In this way, a visual signal is given during the night time or darkness, and the 10 electrical circuit may also include a bell or audible signal for giving a warning when the gates are being closed.

The battery 22 which supplies the electrical energy is preferably located within 15 a concrete well 41, or the like, to protect it from the elements.

The tracks 26 and 27 have the respective rails 28 and 29 which are electrically continuous across the crossing and for suitable distances from the crossing in opposite directions. The other rails of said tracks have insulated sections 30 and 31, respectively, at the crossing, and the respective insulated rail sections 32-33 and 34-35 20 at the opposite sides of the crossing and extending for suitable distance from the crossing in order that the gates will be closed when a train approaches within the determined distance from the crossing.

30 As shown in Fig. 1, the second gate-operating solenoid is indicated 17', and there is associated with each solenoid or motor a controlling means including a switch and electro-magnet for each track. In the arrangement shown, there is an electro-magnet 36 for the track 27 and an electro-magnet 37 for the track 26 associated with the solenoid 17, and similarly, at the opposite side, an electromagnet 36' for the track 27 and 35 an electromagnet 37' for the track 26 associated with the solenoid 17'. There are switches 38, 39, 38' and 39' controlled by the respective magnets 36, 37, 36' and 37', and each set of controlling and operating means 40 has a bus bar 40 or 40' by means of which the proper electrical connections are made between the rail sections and battery and the controlling and gate operating means, as will be apparent by reference to Fig. 1. 45 The electrical connections are apparent from Fig. 1 without detailed description, excepting as hereinafter included in describing the operation of the apparatus.

50 The traffic on the tracks 26 and 27 is toward the right and left, respectively, as seen in Fig. 1. Now, supposing that a train approaches the crossing on track 27 from the right, the wheels and axles of the train will bridge the rail 29 and rail section 35, 55 to electrically connect them. The rails 28 and 29 are both connected by an electrical conductor 42 with one pole of the battery 22, so that the track circuits are closed from the respective insulated rail sections by way 60 of the electrically continuous rails 28 and

29. When the train thus bridges the rail 29 and rail section 35, two gate-closing circuits are established for energizing the solenoids 17 and 17' to close both gates. One circuit includes the battery 22, conductor 42, rail 29, bridge or train connections between the rails, rail section 35, conductor 43, switch 38', contact 44 normally engaged by said switch, conductor 45, solenoid 17', and conductor 46 leading to the battery. 70 The other similar circuit includes the battery 22, conductor 42, rail 29, train connection between the rails, rail section 35, bridge conductor 47 connecting rail sections 34 and 35, conductor 48, switch 38, contact 49 normally engaged by the switch 38, conductor 50, solenoid 17 and conductor 51 leading to the battery. The solenoids 17 and 17' are thus energized, and will close the gates and hold them closed when the train is approaching the crossing. When the train reaches the crossing, the gates are released so as to open. This is caused by the fact that the train bridges the rail 29 and rail section 31 at the crossing, which closes or establishes two gate-releasing or opening circuits. One circuit includes the battery 22, conductor 42, rail 29, train connection or bridge between the rails, rail section 31, conductor 52, magnet 36' and conductor 46. The other corresponding circuit includes the battery 22, conductor 42, rail 29, train connection, rail section 31, conductor 53, magnet 36 and conductor 51. The magnets 36 and 36' are thereby energized to attract the switches 38 and 38', respectively, so as to remove said switches from the contacts 44 and 49 and bring them against the respective contacts 54 and 55. The circuits of the solenoids 17 and 17' are thereby opened by the switches 38 and 38', and the solenoids will therefore become deenergized, and the gates can therefore return to open position. Then, as the train leaves the crossing, the circuits of the solenoids are 100 kept open, to avoid the reclosing of the gates as the train leaves the crossing. Thus, when the train bridges the rail 29 and rail section 34, this will complete two open gate maintaining circuits, it being noted that the magnets 36 and 36' are energized as the train moves from the rail section 31 to the rail section 34. One circuit includes the battery 22, conductor 42, rail 29, train connection, rail section 34, conductor 48, switch 38, contact 56, magnet 36 and conductor 51. The other corresponding circuit includes the battery 22, conductor 42, rail 29, train connection, rail section 34, conductor 47, rail section 35, conductor 43, switch 38', contact 55, magnet 36' and conductor 46. This maintains the magnets 36 and 36' energized while the train is leaving the crossing along the rail section 34. The rail section 34 is used to protect the crossing 110

should a train back up on the track 27 from the left, inasmuch as the gates will be closed in identically the same manner as if the train approached from the right on track 27, because the rail sections 34 and 35 are connected by the bridge conductor 47. It is therefore necessary to keep the circuits of the solenoids open while the train is leaving the crossing because of the use of the insulated rail sections at the opposite sides of the crossing. When the train leaves the rail section 34, the circuits last described will be opened, and the magnets 36 and 36' will become deenergized, releasing the switches 38 and 38' which will move back against the respective contacts 49 and 44, whereby the approach of another train toward the crossing or the backing up of the train which has left the rail section 34, will again close the gates.

The operation is substantially the same when a train approaches the crossing on the track 26 from the left, excepting that the magnets 37 and 37' and switches 39 and 39' are used instead of the magnets and switches as above described in connection with track 27.

Thus, when the train moves on the rail section 32, two gate-closing circuits are established. One circuit includes the battery 22, conductor 42, rail 28, train connection, rail section 32, conductor 57, switch 39, contact 58 normally engaged by said switch, conductor 59, solenoid 17 and conductor 51. The other circuit includes the battery 22, conductor 42, rail 28, train connection, rail section 32, bridge conductor 60 connecting the rail sections 32 and 33, conductor 61 leading from the rail section 33, switch 39', contact 62 normally engaged by

said switch, conductor 63, solenoid 17' and conductor 46. This will energize the solenoids and close the gates. When the train reaches the crossing the circuits of the solenoids are broken in the same manner as hereinbefore described in connection with track 27.

The gate releasing or opening circuits are established by the bridging of the rail 28 and rail section 30 by the train. One circuit includes the battery 22, conductor 42, rail 28, train connection, rail section 30, conductor 64, magnet 37 and conductor 51. The other circuit includes the battery 22, conductor 42, rail 28, train connection, rail section 30, conductor 65, magnet 37' and conductor 46. The magnets 37 and 37' are thus energized and will attract the respective switches 39 and 39' away from the contacts 58 and 62, so as to open the circuits of the solenoids and release the gates so that said gates move open. The switches 39 and 39' are thereby moved against the respective contacts 66 and 67, in order that when the train leaves the crossing, the bridging of the rail 28 and rail section 33 will establish open gate maintain-

ing circuits. One circuit includes the battery 22, conductor 42, rail 28, train connection, rail section 33, conductor 60, rail section 32, conductor 57, switch 39, contact 66, magnet 37 and conductor 51. The other circuit includes the battery 22, conductor 42, rail 28, train connection, rail section 33, conductor 61, switch 39', contact 67, magnet 37' and conductor 46. The magnets 37 and 37' are thus kept energized when the train leaves the crossing until it passes from the rail section 33, which opens the circuits of said magnets and permits the switches 39 and 39' to again move against the contact 58 and 62, respectively. Thus, should the train back up toward the crossing and move on the rail section 33, the gate closing circuits will be established, the same as when the train moved on the rail section 32, it being noted that the rail section 32 and 33 are connected by the bridge conductor 60. The gates will therefore be closed and opened by the traffic in either direction on either track.

The arrangement is such, furthermore, that when a train is on either track and is separated at the crossing to enable traffic to pass across the tracks, such as sometimes happens when a long train is stopped at the crossing, the gates will be closed by the approach of a train on the other track. Thus, supposing a train has moved to the crossing on the track 27, as above described, causing the gates to be closed and then opened, with the magnets 36 and 36' energized, the train can be broken at the crossing and the sections thereof positioned on the rail sections 34 and 35. This will enable vehicles and pedestrians to cross the tracks, but should a train approach the crossing on the track 26, the gates will be closed because the switches 39 and 39' are in position for the closing of the circuits of the solenoids 17 and 17', respectively. Thus, the gates will be closed, in any event, by the approach of a train toward the crossing, whether or not there is a broken train on the other track for the passage of traffic, or whether the train on the other track is located at or leaving the crossing. In other words, when a train is at the crossing or leaving same on one track, this does not in any way interfere with the closing of the gates by a train approaching on the other track, and the arrangement can be multiplied for use on any number of tracks.

Such precautionary measures are especially desirable when a train is broken at the crossing on one track and traffic permitted on the road or thoroughfare across the tracks, so that a clear view along the other track is blocked or obstructed by the broken train.

The gates, although weighted or biased to swing open, move easily to closed positions so as to not require a great deal of elec-

tricity. The gates are made of a light weight material, such as aluminum, and are hinged at the top and bottom so as to swing open and closed easily. The weight of the gates is such that they will swing open when a train passes over them, and will close when a train leaves the crossing. The gates are made of a light weight material, such as aluminum, and are hinged at the top and bottom so as to swing open and closed easily. The weight of the gates is such that they will swing open when a train passes over them, and will close when a train leaves the crossing.

The gates are made of a light weight material, such as aluminum, and are hinged at the top and bottom so as to swing open and closed easily. The weight of the gates is such that they will swing open when a train passes over them, and will close when a train leaves the crossing.

The gates are made of a light weight material, such as aluminum, and are hinged at the top and bottom so as to swing open and closed easily. The weight of the gates is such that they will swing open when a train passes over them, and will close when a train leaves the crossing.

The gates are made of a light weight material, such as aluminum, and are hinged at the top and bottom so as to swing open and closed easily. The weight of the gates is such that they will swing open when a train passes over them, and will close when a train leaves the crossing.

The gates are made of a light weight material, such as aluminum, and are hinged at the top and bottom so as to swing open and closed easily. The weight of the gates is such that they will swing open when a train passes over them, and will close when a train leaves the crossing.

The gates are made of a light weight material, such as aluminum, and are hinged at the top and bottom so as to swing open and closed easily. The weight of the gates is such that they will swing open when a train passes over them, and will close when a train leaves the crossing.

trical energy, and the apparatus is otherwise simple in operation and construction. The apparatus is also adaptable for use on either steam or electric railways.

5 The electromagnetic switches are all alike, and one of them is shown in detail in Figs. 4 and 5. The electromagnet 36 is mounted on a base 70 from which a bracket 71 and a pair of posts 72 and 73 project. An armature 74 is connected at one end to the end of the bracket 71 by means of a resilient flex plate 75, permitting said armature to swing toward and away from the pole of said magnet. A leaf spring 76 is also fastened 10 to the end of the bracket, and an arched member 77 bears at one end against the spring and at its other end against the armature, with an adjusting screw 78 extending through said member 77 and threaded within the armature. By tightening the screw 78, the spring 76 and armature 74 are moved toward one another, thereby increasing the tension of the spring exerted against the armature for moving the armature away 15 from the magnet. Thus, by adjusting the screw 78, the tension of the spring and armature is regulated. The armature 74 carries insulated contacts 79 and 80, and contact fingers or springs 81 and 82 are fastened to 20 the ends of the respective posts 72 and 73, with the free end of the armature located between said contact fingers and the contacts or buttons 79 and 80 are also reversed. The respective conductors are connected to 25 said contacts and fingers, and when the magnet is deenergized, the armature 74 in moving away from the magnet will bring the contact 79 against the finger 81, whereas when the magnet is energized and the armature 30 74 attracted to the magnet, the contact

80 is brought against the finger 82 thereby opening and closing the corresponding circuits.

Having thus described the invention, what is claimed as new is:—

45 The combination of two railroad tracks, one rail of each track having an insulated rail section at the crossing and other insulated rail sections at both sides of the crossing, a source of electrical energy connected to the other rails of the tracks, crossing gates at opposite sides of the tracks, an electric motor for operating each gate, a pair of electro-magnets associated with each motor, the motors and electro-magnets each having one terminal connected to the source of electrical energy, electrical connections between the first named insulated rail section of each track and the other terminals of one electro-magnet of each pair, switches controlled by said electro-magnets, electrical connections between the other insulated rail sections of each track and the switches of the corresponding magnets, said switches being normally connected with the other 50 terminals of said motors and when attracted by the magnets opening said connections and making connections with the last named terminals of the corresponding magnets, whereby a train approaching the crossing in either direction on either track will operate both gates, and whereby both gates are also operated when a train approaches the crossing on one track with a train on the other track which has moved to or beyond the 55 first named insulated rail section thereof at each crossing.

60 In testimony whereof I have signed my name to this specification.

65 ARO M. HARVEY.
